UNITED STATES PATENT OFFICE.

JOHN C. QUINN, OF STATEN ISLAND, NEW YORK, ASSIGNOR TO QUINN OIL BURNER CORPORATION, OF NEW YORK, N. Y., A CORPORATION OF NEW YORK.

OIL BURNER.

Application filed November 7, 1922. Serial No. 599,534.

To all whom it may concern:

Be it known that JOHN C. QUINN, a citizen of the United States, residing at 28 Fort Place, St. George, Staten Island, in the county of New York and State of New York, has invented certain new and useful Improvements in Oil Burners, of which the following is a specification.

This invention relates to certain new and useful improvements in hydro-carbon burners adapted to burn more especially the coarser grades of crude oil, though it can be used to burn oil partly refined, and it more particularly relates to the class of burners to be installed for power and manufacturing plants using steam boilers, and in furnaces such as are used for the heating of houses during cold weather, though it may, of course, be utilized for marine propulsion and other purposes.

One of the objects of my invention is to provide a burner which may be used with crude oil; especially crude oil of the coarser and cheaper grades.

A number of hydro-carbon burners have been put upon the market which will burn oil quite well if it is of the better and finer grades, but with oil of the coarser grades, or only partly refined, their operation is not satisfactory, resulting in the production of a great deal of smoke.

Another object of my invention, therefore, is to produce a device which overcomes this difficulty and which at the same time will not become clogged by use, or easily get out of order.

A further object of my invention is to so construct it that without the employment of special means to obtain a forced draft, I obtain the same result by the proper arrangement of the space between the vaporization plate and the depending cone, as herein-after more fully described.

A still further object of my invention is to construct a device which operates with high efficiency, has great durability of construction and yet possesses marked simplicity as a whole and in respect of each of its component parts, so that its manufacture is economically facilitated both as regards production of the parts and their assembly.

With these and other objects in view which may be incident to my improvements, the invention consists in the parts and combinations to be hereinafter set forth and claimed,

with the understanding that the several necessary elements comprising my invention, may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings:

Figure 1 is a side elevation of a coal furnace partly in section, showing my improved burner located therein;

Fig. 2 is a detail view of the valve for diminishing the flow of the oil to the burner;

Fig. 3 is an enlarged vertical longitudinal sectional view of my burner in detail;

Fig. 4 is a cross sectional view taken on the line 4—4 of Fig. 3, looking in the direction of the arrows;

Fig. 5 is a similar view taken on the line 5—5 of Fig. 3;

Fig. 6 is a similar view taken on the line 6—6 of Fig. 3;

Fig. 7 is a detail sectional view showing the orifice under each foot of the baffle plate, and

Fig. 8 is a vertical longitudinal sectional view of a modified form of my device.

The numeral 1 represents a steam furnace boiler of the usual or any approved construction such as is used for heating houses, the same being provided upon the top with a steam pressure gauge 2. The numeral 3 represents a steam pressure diaphragm provided with a support 4 in which rests the lever 5 pivotally attached at one end 6, to an upright 7 bolted or otherwise secured to the top 8 of the boiler.

The other end of the lever 5 is provided with several niches or kerfs 9, from one of which hangs, a weight 11, by means of a metallic strap.

The extreme end of the lever is pivotally connected to a rod 12 having a turn-buckle 13, by means of which the length of the rod may be properly adjusted with respect to the bell-crank lever 14 at its lower end, and to a valve 15 located within the pipe coupling 16. This valve is illustrated more particularly in Fig. 2, and its purpose is to lessen

the flow of oil to the burner (to be herein-after more particularly described) when the steam pressure becomes too great, and as seen in Fig. 2, it does not entirely cut off the flow as there is a groove 17 provided in the seat of the valve which permits a small flow in order that the fire will not become extinguished, though its strength is greatly diminished.

10 Extending downwardly from this valve is a pipe 18, and at its lower end another coupling 20, having a needle valve 21 with a pointer 22 which passes over the arcuate plate 23, the valve being adjusted by turning 15 the hand wheel 24.

It will be observed that the pipe 18 extends still lower, as seen at 25, into the coupling 26 where it turns at right angles, extending to the coupling 27, then upwardly 20 into the globe valve 28, thence to a coupling 29 where it turns at right angles for a short distance and enters the oil tank 31. This tank is provided with a filling pipe 32 extending upwardly therefrom and adapted 25 to be connected with a source of oil supply.

As seen in Fig. 1, this tank is mounted upon a suitable support or shelf 33 attached to one of the side walls of the room in which the furnace is located, but the arrangement 30 of this may be in any suitable and satisfactory manner.

The furnace is provided with the usual openings having door closures; 34 being the door to be opened when it is desired to clean 35 out the flues; 35 the door which is opened when it is desired to coal the furnace, it being understood that for purposes of illustrating, my device is herein shown as applied to an ordinary coal-burning furnace; 40 and 36 is the door for regulating the draft from the front of the furnace through the grate bars 37 and the flame to the pipe 38 leading from the furnace to the chimney.

The numeral 40 represents a fuel supply 45 pipe running from the valve 16 to the burner proper; and the numeral 41, an overflow pipe which runs from the burner to the overflow can 42 hanging from the hooked end 43 of the lever 44, to whose other end is 50 attached a weighted ball 45. The lever 44 is fulcrumed upon the valve 46 and when the weight of the overflow oil is more than sufficient to balance the weight of the ball, the valve 46 shuts off the flow of the fuel from 55 the tank 31 and the flame of the burner is extinguished.

Referring to Fig. 3, the burner consists of a circular base plate or pan 47, provided with orifices 48 through which extend headed bolts 49 whose lower ends protrude through and below the grate bars of the furnace and are there secured by means of nuts and washers, as clearly seen in Fig. 1, which firmly hold the burner in place.

65 Extending upwardly from the base plate

and equi-distantly located each from the other, are legs 50, with an annular plate 50' fitting loosely over them, and between the legs and extending upwardly from the base plate, is a metallic wall 51 cast integrally with the base plate. At the center of the base plate is a tubular air nozzle 52 provided with slotted openings 53 and 54, for the admission of air from below the grate bars into the combustion chamber.

Located upon the base plate 47 is a metallic vaporizing plate 55, provided with integrally cast lugs 56 which enable it, when placed upon the base plate, to rise slightly above it, and leave space beneath for the oil. 75 The base plate, metallic annular wall 51 and the vaporizing plate resting on the base plate in effect comprise a retort, since the heat directed on the vaporizing plate causes the oil underneath the plate and contained 80 within the enclosure of the base plate and annular wall 51 to become vaporized, and the gas generated rises and unites with the oxygen of the air to produce a very hot flame.

90 Mounted on top of the legs 50 is the plate 50', above referred to, extending to the side walls of the furnace, covered with a layer of fire-clay. Resting on the inner edge of said plate is the flange 56' of a depending 95 cast iron cone 57 adapted to be located over the tubular air nozzle heretofore described, said flange being adapted to rest upon the legs 50.

Just exterior to the cone and at equidistantly located points, are openings 58 for the passage of air, and located upon the top of the cone 57, but separate and distinct therefrom, is a baffle plate 60 to spread the flame, having legs 61 provided with 100 passages corresponding to the openings 58, the legs being so arranged as to correspond with the openings below and to set over the same. In this way their position may be somewhat changed, as seen in Figs. 4 and 7, 110 and the air at such points partly cut off. It will be noted that the raised edge 62' of the vaporizing plate 55 adjacent the tubular nozzle 52 is higher than the edge 62, so that no oil can flow against the sides of the 115 nozzle.

This burner is designed to efficiently burn a given quantity of oil in a given period, and will be made in a number of sizes for the varying requirements of service. In order to obtain complete combustion, a predetermined quantity of air under high velocity is delivered to a given quantity of oil. This condition is obtained by constructing the burner of a definite proportional size, with 125 a proper opening between the outside of the cone 57 and the wall 51, and also for the control and delivery of the required volume of free air at proper velocity or pressure at the area or field of combustion. The exterior 130

diameter of the vaporizing plate 55 in the device from which the drawings herewith were made, is $5\frac{1}{2}$ inches, and the interior diameter of the cone 57 at its lowest edge, 5 is $3\frac{1}{2}$ inches. From the inner cone to the gasifying or vaporizing plate on the bottom of the burner base the space should be substantially $\frac{1}{2}$ ", and it has been found in practice that a variation of $\frac{1}{16}$ " to $\frac{1}{8}$ ", 10 $12\frac{1}{2}$ to 25% either way will render the operation less inefficient for the following reasons:

One pound of oil containing approximately 16000 B. t. u. (British thermal units) 15 requires approximately three and one-half pounds of pure oxygen for complete chemical action in the production of CO_2 gas and water vapor according to the following equation illustrating the combustion of one 20 heavy oil:

To obtain this quantity of oxygen approximately fifteen pounds of free air, or 25 approximately 185 to 200 cubic feet in volume, must be fed to the fire. Should the indicated space be appreciably less than $\frac{1}{2}$ ", the required amount of air will be insufficient, and the velocity will be so high as to 30 make not a steady flame, but rather a series of rapid explosions with an undesirably noisy effect. Should this space be appreciably more than $\frac{1}{2}$ ", an excessive amount 35 of air is admitted and since this must be heated the efficiency of the burner and the heat given up to the boiler or stove, etc., is diminished. With this optimum distance of $\frac{1}{2}$ " fixed, it follows of course that the 40 burner can take care of a variation of a few per cent in the oil consumption during the short periods of adjustment thereof by the steam pressure diaphragm 3, when the steam pressure is slightly too high or too 45 low.

The size of each burner is based on the average amount of oil consumption for the imposed duty in each installation, as for 50 carrying a constant steam pressure in a boiler. In every case, however, the proportionate distance between the inner cone and vaporizing plate is maintained. Analysis shows that this important feature of my invention automatically makes the volume of 55 air coming through the space 65, and the volume of vapor issuing from under the vaporizing plate 55, both proportional to the circumference of the vaporizing plate 55 and therefore constant in the ratio needed 60 for most efficient combustion.

It will be noted that the edge 62 of the plate 55 is beyond the lower edge of the inner cone 57, and this arrangement automatically 65 causes the draft of air coming down the space 65 to become thoroughly ad-

mixed with the smaller volume of oil vapors issuing from under the plate 55 before such air and oil vapors reach the point of combustion. Furthermore, the introduction of air through 52 into the combustion chamber 70 and the use of the top baffle plate cause the incoming air and oil vapor to form a better combustion mixture and practically a solid blue flame filling such combustion chamber and issuing therefrom through the 75 port-holes of the baffle plate.

To the above there is this one exception as follows: It will be observed that there are several set-screws 55' shown in the flange 56' resting upon the supporting standards 80 which are for use only in the case of a high wind to lower the cone so as to reduce the aperture between it and the vaporizing plate 55 to $\frac{7}{16}$ or $\frac{3}{8}$ of an inch, and where there is a lack of wind, to increase the distance 85 to $\frac{9}{16}$ or $\frac{5}{8}$ of an inch. In other words, this adjustment is to be made only under abnormal conditions in order to maintain the desired ratio of air to oil discussed above. 90

The operation of my device is as follows:

Oil is admitted to the burner through the pipe 40, and the vaporizing plate on the base plate of burner is formed to allow $\frac{1}{8}$ " space on its under surface for the accumulation of the fuel oil. In starting combustion, oil is allowed to flow in this space until it is filled and rises over the outer edge and flows over the top surface of plate; a torch or piece of oil-soaked rag or waste to 100 which a match has been applied is then thrown into the burner which produces a rather smoky combustion for the period of from one to two minutes, after which the combustion becomes perfect with an entire 105 absence of smoke. The free oil on top of plate soon burns off and the plate becomes highly heated. From this point the oil, being fed in small quantity, is turned into gas by the heat of the plate, and this gas, rising 110 at the periphery of the plate, is met by the incoming preheated air, producing a combustion which is practically perfect.

Fig. 8 shows a modified form of my invention and it is to be observed that the base plate is not perforated as shown in Fig. 3, and the tubular nozzle 52 is entirely absent. Further, the cone 57' which in Fig. 3 is imperforate on its sides, is in this instance provided with orifices 63 and 64. This form 115 of the device has been tried out and found to work satisfactorily, but it is not the preferred form and does not have as strong a draft as the device illustrated in Fig. 3.

With the arrangement shown, I secure 125 what may be described as a forced draft, at the point 65', though no operating mechanism for this purpose is employed.

While I have shown and described the preferred embodiment of my invention, I wish 130

it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

- 10 1. In a device of the character described, the combination with a base plate, an up-standing cylindrical wall upon its upper surface cast integrally therewith, supporting standards rising above the cylindrical wall, and a vaporizing plate adapted to rest upon the base plate, of a cone adapted to rest upon the supporting standards and to depend therefrom, a flanged rim on the cone having air openings therein a baffle plate adapted to rest upon the cone and to spread the flame outwardly, and legs on said baffle plate adapted to fit over said openings having passages therethrough to correspond with the openings in the flanged rim where-
25 by a portion of the air may be diverted to the periphery of the baffle plate.
- 20 2. In a device of the character described, the combination with a base plate, an up-standing cylindrical wall upon its upper surface cast integrally therewith, and supporting standards rising above the cylindrical wall, a vaporizing plate adapted to rest upon the base plate, of a cone adapted to rest upon the supporting standards and
30 to depend therefrom interiorly of said cy- lindrical wall, a flanged rim on the cone, having openings therein and a removable baffle plate adapted to rest upon the cone and to spread the flame outwardly, and legs
35 on said baffle plate provided with openings adapted to fit over said openings in the rim of the cone.
- 35 3. In a device of the character described, the combination of a base plate, a tubular air nozzle located thereon and extending therethrough, an upstanding cylindrical wall upon its upper surface, a vaporizing plate adapted to rest upon the base plate, supporting means, a cone carried by said supporting means, said cone being spaced from the cylindrical wall for the admission of air between the wall and the cone, and a baffle plate adapted to rest upon the cone and spread the flame outwardly.
- 45 4. In a device of the character described, the combination with a base plate, a tubular air nozzle located thereon, an upstanding cylindrical wall upon its upper surface and supporting standards rising above the cylindrical wall, and a vaporizing plate adapted to rest upon the base plate, of a cone adapted to rest upon the supporting standards and to depend therefrom, a flanged rim on the cone having air openings therein and a baffle plate adapted to rest upon the cone and to

spread the flame outwardly, legs on said baffle plate adapted to fit over said openings having passages therethrough to correspond with the openings in the flanged rim whereby a portion of the air may be diverted to the periphery of the baffle plate.

5. In a device of the character described, the combination of a base plate, an upwardly extending cylindrical wall upon its upper surface, supporting standards rising above the cylindrical wall, a loosely mounted vaporizing plate adapted to rest upon the base plate, a cone adapted to rest upon the supporting standards and to depend therefrom leaving a passageway between the cylindrical wall and the cone, and a baffle plate adapted to rest upon the cone and spread the flame outwardly.

6. In a device of the character described, the combination with a base plate, an up-standing cylindrical wall upon its upper surface, supporting standards rising above the cylindrical wall, and a vaporizing plate adapted to rest upon the base plate, of a cone adapted to rest upon the supporting standards and to depend therefrom, a flanged rim on the cone having air openings therethrough and a baffle plate adapted to rest upon the cone and to spread the flame outwardly, and legs on said baffle plate adapted to fit over said openings having passages therethrough to correspond with the openings in the flanged rim.

7. In a device of the character described, the combination of a base plate, an upstanding cylindrical wall upon its upper surface cast integrally therewith, supporting standards rising above the cylindrical wall, a vaporizing plate, and means to space the vaporizing plate from the base plate, and an adjustable cone adapted to rest upon the supporting standards and to depend therefrom, and spaced from the cylindrical wall to provide a passageway.

8. In a device of the character described, a container, a vaporizing plate therein, an adjustable hollow depending member, and means to support the latter above the vaporizing plate, the wall of the container forming with the depending member a passageway for directing a heated current of air against the vaporizing plate and the depending member and the vaporizing plate forming another passageway.

9. In a device of the character described, a container, a vaporizing plate near the base of the container and spaced therefrom, a depending member forming with the container an air passage, and adjustable means to support the depending member above the vaporizing plate, whereby its height above said plate may be varied.

10. In an oil burner, the combination with means for vaporizing oil, of an upwardly extending wall a hollow depending member

cooperating with said upwardly extending wall to direct heated air against said vaporizing means, a support for the hollow depending member, and means cooperating with said support for varying the distance between the hollow depending member and the vaporizing means.

11. In an oil burner, a base plate, a wall extending upwardly therefrom, a vaporizing structure, and an adjustable hollow depending member, the wall and the depending member forming a passageway for directing a heated current of gas against the vaporizing structure and the depending member and

the vaporizing structure forming another 15 passageway.

12. In an oil burner, a base plate, a wall extending upwardly therefrom, a vaporizing structure, a hollow depending member, and means for varying the distance of the lower 20 edge of the depending member from the base plate, the wall and depending member forming a passageway for directing a heated current of gas against the vaporizing structure.

In testimony whereof I affix my signature.

JOHN C: QUINN.
